UNITED STATES PATENT OFFICE

LESLIE DANA, OF ST. LOUIS, MISSOURI, ASSIGNOR TO CHARTER OAK STOVE AND RANGE COMPANY, A CORPORATION OF MISSOURI

STOVE CONSTRUCTION

Original application filed April 4, 1928, Serial No. 267,401. Divided and this application filed March 21, 1929. Serial No. 348,950.

This invention pertains to cast iron or cast steel cooking stoves or ranges, particularly domestic ranges of the type burning either coal or wood, and aims generally to improve the construction thereof. Certain other objects of the invention are to obtain more uniform distribution of heat to the oven, to form the parts so that they may be readily enamelled, to improve the assembly of the stove-body and base, and so to form the construction as to obtain greater simplicity and accessibility of parts and greater ease in cleaning.

Other objects and advantages of my invention will be apparent from the following specification and accompanying drawings of a preferred embodiment illustrating the principles thereof, wherein

Fig. 1 is a front sectional view taken through the oven flue and fire box to show the structural features and the relation of the flue system to the rest of the stove structure;

Fig. 2 is a sectional view taken on lines 2—2 of Figs. 1 and 3;

Fig. 3 is a horizontal sectional view taken on line 3—3 of Fig. 1; and

Fig. 4 is a detail view of the bottom baffle, showing the parts in cross section on the line 4—4 of Fig. 3.

General features

As set forth in my prior application Serial No. 267,401 filed April 4, 1928 of which this application is a division, the drawings show a cooking range of the type having at one end a fire box 1 and ashpit 2 (see Fig. 1), together constituting the combustion chamber, and separated by a shaking grate comprising a plurality of bars 3, 3. Adjacent to the combustion chamber is an oven 4, around which the products of combustion may circulate; and the stove body is supported by a flat top 5 of convenient design, and supported on a base comprising four legs 6 joined by intermediate sections 7, 8. Accessory features, such as shelves, warming ovens, and the like (not shown) may be attached or omitted as desired, these

features being well known and forming no part of the invention.

For convenience I herein show and describe my stove as having the fire box at the left end, which is usual in the art.

The external casing comprises the top 5 and five principal plate members, namely four side or end walls 10, 11, 12, and 13, and a bottom 14, all fitted to each other by concealed flanges and bolted together interiorly, making externally flush joints. Each of the plate members will ordinarily be an integral casting. The exposed surface of the casing may be enamelled, except for the top 5, which is usually of smooth black or polished finish with a quarter-round edge rail, preferably polished to match. The bottom 14 and back 13, which are ordinarily concealed from view, may be of rough black finish.

All connecting elements, such as bolt heads, lugs and so on, pertaining to the front and ends are arranged not to protrude through or be visible on the outside, all door hinges and latches are concealed, and all handles and knobs are made as inconspicuous as possible, the principal ones being cast integral with the parts to which they apply, and exteriorly stream-lined so that the visible surface will be almost entirely free from projections, thus resembling in appearance a single polished block of enamel.

As set forth in my above mentioned application the artistic effect and unitary appearance of the range are generally enhanced by the use of smoothly rounded exterior surfaces on the top, front and sides, which also facilitate the enameling of the exposed surfaces.

In general, the heating passages in the stove are arranged to extend from the fire box 1 (which is adapted to burn either coal or wood, through the use of my duplex grates 3) above the oven 4, downwardly at the opposite end of the stove adjacent the outer end wall 12, below the oven adjacent the stove bottom 14, rearwardly and outwardly through the flue opening 15 and flue

casing 16, and thence to the chimney connection through the flue pipe opening 17.

Provision is made for directly bypassing the heated gases to the flue casing 16 by means of a draft opening 18 at the top and to the rear of the oven, controlled by a control slide 34; and the construction also provides means, which may take the form of a movable baffle plate 19, positioned between the oven bottom and the stove bottom 14, for directing the flow of gases to obtain more uniform heating of the oven.

The oven

15 The oven 4 comprises a unitary transverse heat conducting vertical plate 20, which extends the full width of the interior of the stove casing, from the bottom 14 to within a short distance of the top 5. This plate 20 forms the right wall of the combustion chamber and the left end of the oven, and separates the oven and bottom flue space from the fire box and ashpit chamber, besides supporting the oven top 21 and oven floor 22. As illustrated in Fig. 1, this plate, together with the oven top, furnishes a base for a post 23, giving intermediate support to the stove top 5. From the level of the oven bottom to the level of the fire box bottom, this plate is bulged outward toward the fire box, as shown at 24, Fig. 1, increasing the capacity of the lower part of the oven. The inside of the bottom curve 25 of this bulge forms a part of the oven floor, and is flanged to fit with the oven floor plate 22, which is appropriately secured thereto. The outside of the top curve 26 of the bulge constitutes part of the fire box support. The right end wall 27 of the oven 40 is supported, together with the right end of the bottom 22, by lugs 28, on the front and back plates 11 and 13 of the exterior casing. The upper surface of the oven top plate 21 is provided with cross-ribs 29, and 45 shelf holding lugs or ribs 30 are cast on the inside of the left and right walls, thereby strengthening the oven structure, as well as providing permanent and rigid means for sustaining the shelves.

50 All the corners of the oven are rounded as shown in the drawings, and the floor plate 22 is corrugated, as best shown in Fig. 2, to assist in heat transference and to compensate for expansion and contraction.

Flue system

Referring to Figs. 2 and 3, the draft connection to the stove pipe and chimney, above mentioned, is by means of the trough-like casting or flue piece 16 fitted on the back of the oven extension 31, covering almost the entire width of the oven back, and reaching from the bottom of the stove casing to just below the top rear rail. Suitable means for a substantially air-tight fit

are provided, herein shown as flanges 32, best seen in Fig. 3. The top flue 18 and the bottom flue 15, beneath the oven, lead into the casing 16, from which products of combustion are carried away as usual through the hole 17 in the flue piece 16 near its top, which is preferably surrounded by a pipe collar 33. Opening 18 is provided with a kindling damper 34, as shown in Figs. 1 and 2, by which the flue gases may be directed around the oven, directly to the chimney, or partly in either direction.

To cause complete circulation of heat beneath the oven when the kindling damper 34 is shut, the bottom baffle 19, above mentioned, is hinged to the under side of the oven floor plate 22. This baffle, as shown, extends diagonally into the middle of the space below the oven. A satisfactory baffle construction, herein shown, comprises a cast leaf 19 with an integral pindle at each end of the top, as shown in Figs. 1 and 2. The inner pindle 35 is held loosely in a gudgeon 36 beneath the middle of the oven floor, while the outer pindle 37 passes out through a hole in the back 13, and ends in a down-turned handle 38. When down, as best shown in Fig. 4, the outer edge of the leaf 19 rests against a rib 39 inside the back plate 13 of the stove casing, and constrains the draft passing beneath the oven to follow the path indicated by the arrows A—A, Fig. 3, thus heating the entire floor 22.

In case this is not desired, or in case the space under the oven is to be cleaned out, the leaf 19 may be raised to the dotted line position 19' of Fig. 4, and the handle pulled outward, when it is held up by the top of the rib 40. By raising the leaf and removing the cover 41 of the clean-out opening, the flue space beneath the oven may readily be cleaned in its entirety.

The back of the stove casing is a single cast plate 13 of irregular shape, the bottom and ends being in a common plane and flanged to fit the adjoining plate members, while the top is carried out beyond the bottom, as shown in Fig. 2, partly by a box-like extension forming the end of the fire box 1, and partly by an upwardly and rearwardly inclined overhang 42. As above mentioned, a section of the back plate 13 behind the oven is also extended outwardly, forming a bay 31, constituting a rear extension and back wall of the oven.

The bottom plate 22 is flat on top, with recesses 43 at the corners to receive the lugs 44 and bolts 45 that secure the front and back walls 11, 13 thereto, (see Fig. 3), and with edge flanges 46 of U-shape (Figs. 1 and 2), which form a peripheral top groove into which the bottom flanges 49 of the four side walls fit. The outer wall of the encircling U-shaped flange is formed along its lower edge with a downward shallow

strengthening rib, which at the corners of the stove is widened somewhat to form bearing supports adapted to rest on the corner lugs 48 of the base.

- 5 This construction is particularly advantageous with an enamel-finished stove of the stream-line type because the slightly increased flange depth at the corners raises the stove body just sufficiently to prevent chipping of the enamel along the top of the base and the bottom of the vertical side wall plates, without elevating the body high enough to allow lodgment of dirt thereon, or to break the continuity of appearance.
- 10 15 The flat top surface of the bottom 22 with the depending encircling edge flange, constituting an inverted bottom as compared with the usual construction, avoids catching dirt, and makes the bottom pit easy to 20 keep clean.

The bosses 49 on the underside of the bottom plate 22, one near each corner, allow the stove assembly minus base and legs to be set on a floor or platform, leaving sufficient space for a finger-hold under the edges, thus facilitating handling and minimizing the danger of chipping the enamel. This construction also makes it possible to assemble the stove on the bottom plate 22 with the bottom nuts on the outside, inasmuch as the bosses 49 are of greater depth than the projections of the assembling bolts. The under side of the bottom plate is suitably reinforced, as by a central rectangular rib 35 50, from the corners of which diagonal ribs 51 run to the bosses 49, as best indicated by dotted lines in Fig. 3.

It will be apparent from the foregoing that my improved stove is characterized by 40 compactness and strength combined with a pleasing appearance. The oven construction is such as to permit easy cleaning, by reason of the rounded corners, and its design is such as to utilize the heat advantageously, the oven being nearly surrounded by the bottom draft flue and the wide rear outside flue 16, and also receiving heat transmitted through plate 20 from the combustion chamber.

55 50 From a mechanical standpoint this stove is characterized by a relatively small number of fairly large separate parts, many having combined functions, and by having those parts which are to be enamelled so shaped as to allow the enamel to spread itself freely and smoothly thereon. In this manner difficulties in dipping and baking the enamelled castings are avoided.

60 The cost of assembly is reduced and the speed of setting up is increased by having few parts, and by arranging them so as to hold each other in place thereby reducing the number of bolts required.

65 55 The invention is not limited to the illus-

trative embodiment herein shown and described, but what I claim is as follows:

1. In a cooking range of the type having a fire box and ashpit to one side of and of greater height than an oven, and adjacent said oven in a common external casing, a common wall between said fire box and said oven formed of a unitary casting having its intermediate portion offset from its upper and lower sections, and projecting into said fire box, whereby said upper section narrows the top part of said oven and widens said fire box, said intermediate portion widens the lower portion of said oven, forms a rounded bottom corner therefor, and narrows said fire box below the grates, and said lower portion widens said ashpit, and constitutes a support for one end of the bottom of said oven.

2. In a cooking range, in combination, within a common external casing, an oven, a fire box and ashpit at one end of said oven, connecting flue spaces above, at the other end of, and below said oven, a unitary heat conducting wall separating said fire box and ashpit from said oven, forming the terminal wall of said flue below said oven, and supporting the bottom of said oven and racks therein, said wall comprising three horizontal sections of approximately equal depth, the middle of said sections being offset away from said oven in a plane parallel to the plane of the upper and lower sections.

3. In a cooking range, having a fire box, an ashpit and an oven, as a subcombination, a vertical partition extending from front to rear of the stove, comprising upper, middle, and lower horizontal panels of approximately equal height, said middle panel being offset from said upper and lower panels and joined thereto by curved ledges, said partition constituting the rear wall of the fire box and ashpit, and constituting a side wall and a bottom support of the oven, the upper of said curved ledges forming a part of the bottom of the fire box, and the lower of said ledges forming a curved lower inner edge of the oven, joining smoothly onto the bottom thereof.

4. In a cooking range, in combination, an oven characterized by a corrugated bottom, rounded corners and edges, and a reversely curved plate which supports one side of said bottom and constitutes one of said rounded edges.

5. A corner construction for enamel-finished stoves comprising, in combination, a base-plate, a peripheral flange thereon, a slightly deepened portion on said flange, and a support for said base plate including means to engage said deepened portion of said flange.

6. In a stream-line type of stove, in combination, a bottom plate, upright plates rising therefrom, a base supporting all of said

plates, a peripheral flange on said bottom plate, said flange lying within and concealed by said base, said base having an even upper edge, bottom edge flanges on said upright plates matching said upper edge, concealed supporting members within said base, and means on said peripheral flange coacting with said supporting members whereby to relieve the pressure between said upper edge of said base and said bottom edge flanges.

7. In an enamel-finished stove, in combination, a body, including enamelled walls with inturned enamelled bottom flanges, a bottom plate having an enamelled edge adapted to receive said flanges, a downward peripheral flange on the bottom of said body adapted to fit within said bottom plate and comprising slightly deepened portions in the bottom plate, lugs within said base adapted to support said body by means of said slightly deepened portions, whereby to avoid weight-supporting contact between said enamelled flanges and said enamelled edge but without material separation therebetween.

8. A stove casing including, in combination, a bottom plate and an upright plate rising therefrom, a flange around the periphery of said bottom plate, a groove defined by said flange, an inwardly-extending enlargement of said groove, a flange on said upright plate seating within said groove, a holding element on the inside of said upright plate extending into said enlargement, and securing means fastening said holding element therein, whereby said bottom plate and said upright plate are united into a permanent structure.

9. In combination, in a stove having a body which comprises a bottom plate and upright side members, means for securing said plate and said members comprising a recess below the top surface of said plate, a lug on one of said side members fitting within said recess, and holding means engaging said lug and said bottom plate, said lug and said holding means not rising above the top surface of said plate.

10. In a stove casing which includes a bottom plate and upright members rising therefrom, recesses in said bottom plate below the top surface thereof, lugs on said upright members engaging said bottom plate within said recesses, securing means passing through said lugs and said bottom plate, said recesses, said lugs, and said securing means being so proportioned that said lugs and said securing means do not rise above the top surface of said bottom plate.

11. In a stove casing of the type comprising a bottom plate and upright side members, in combination, a downward flange around the periphery of said plate, reinforcing ribs on the bottom of said plate, and

supporting bosses on the bottom of said plate, recesses on the top of said plate below the top surface thereof, and means coacting with said recesses to secure said side members thereto, all of said securing and reinforcing means lying between the plane of the top of said bottom plate and the plane of the bottom of said bosses.

In testimony whereof, I have signed my name to this specification.

LESLIE DANA.
